UNITED STATES PATENT OFFICE.

HENRY H. HARRISON, OF NEW YORK, N. Y.

COPYING DEVICE.

No. 823,860.

Specification of Letters Patent.

Patented June 19, 1906.

Application filed January 6, 1906. Serial No. 294,871.

To all whom it may concern:

Be it known that I, HENRY H. HARRISON, a citizen of the United States, and a resident of the city of New York, borough of Manhattan, in the county and State of New York, have invented a new and Improved Copying Device, of which the following is a full, clear, and exact description.

The invention relates to a copying device intended for use in connection with the so-called "hectograph copying composition."

It is particularly designed as a hand-operated device, although it may be made of a large size and arranged to operate on and having a geared connection with a permanent platen, as will be fully understood by persons skilled in the art.

My present invention particularly resides in the manner of applying the hectograph composition to a fabric or other flexible holder and to certain peculiar devices for adjustably securing this holder to the body of the copying device.

Various other features are involved, all of which will be fully set forth hereinafter, and particularly pointed out in the claims.

Reference is to be had to the accompanying drawings, which illustrate, as an example, the preferred embodiment of my invention, in which—

Figure 1 is a side view of the invention. Fig. 2 is a top view of the same, and Fig. 3 is a detail section on the line 3-3 of Fig. 2.

The body 10 of the device has its lower or working surface 10^a of essentially semicircular or arc-shaped contour, while the opposite or upper part of the body may be open, as indicated at 11, for lightness of construction, although this is not essential. The said body is provided at its upper side with a handle 12, which spans the opening 11 and facilitates the manipulation of the copying device. As shown best in Fig. 3, the hectograph composition 14 is applied to the middle portion of a sheet of fabric or other durable flexible material 15, said composition being made permanently to adhere thereto, and the back of said sheet 15 of fabric or other material is provided with a covering 16 of oil composition or other impervious substance. These materials 14, 15, and 16, arranged as described, form a mass of hectographic material permanently secured to a tough flexible sheet, which, owing to the oil composition on the back thereof, will not permit the passage of moisture and will always present a dry clean

surface. Said sheet 15, with the materials 14 and 16 applied thereto, as described, is applied to the outer or working surface of the body 10 with the hectographic material on the outer side. The ends of said sheet 15 are not covered with the hectographic material and wound, respectively, over rollers or drums 17 and 18. These rollers are arranged, respectively, at the ends of the copying device. The roller 17 is mounted to turn in brackets 19, which are fastened to the sides of the body and project above the same, the roller being preferably slotted to receive the end of the fabric 15, as indicated in Fig. 3. Said roller 17 is provided with a spring-arm 20, and this is adapted to be held in a hook 21, suitably sustained on the body. As here shown, it is secured by a shank 22, which is fastened to one side of the body and projects horizontally between the opening 11 thereof. Said hook 21 may be otherwise positioned on the body without departing from the spirit of my invention.

The roller 18 is mounted in bracket-plates 23, which project upward from the end of the body opposite that on which the roller 17 is located. This roller 18 is also slotted, as shown, and is provided at one end with a knob 24 facilitating turning the roller. The roller is also provided with a ratchet 25 at the end adjacent to the knob, and this is engaged by a pawl 26, which is fitted on one of the bracket-plates 23 and pressed yieldingly into active position by a spring 27.

In the use of the device the sheet 15 has the ends engaged with the rollers 17 and 18, and the roller 18 is then turned so as to taunt the sheet and draw the hectographic material firmly over the working surface of the body 10. After this has been done the final tensioning of the fabric sheet 15 and its attached substance is effected by turning downward the spring-arm 20 into the position shown in Fig. 1 and engaging the same with the hook 21. This completes the operation of firmly drawing the fabric over the curved edge of the body 10, and the copying device is now adjusted for operation. The copying operation is carried out in the usual manner, the copy being impressed on the hectograph material 15 and transferred therefrom by rocking the copying device over the sheet on which the copy is to be impressed. The ink of the copy may be washed off of the hectograph material from time to time, as will be fully understood from the prior art, and any number of

separate sheets of the material 15, with the hectographic material applied, may be kept on hand and transferred from time to time, as desired or required.

5 It will be seen that the device provides a very simple and convenient means of holding the hectographic material and enables the copy to be easily and quickly impressed upon any number of successive sheets. The device may be constructed in various sizes from small hand size up to such size as would be too heavy to admit of readily lifting the device, in which case it should be mounted on a permanent platen and, if desired, connected therewith by a segmental gear on the body of the device and a rack extending along the edge of the platen.

Having thus described the preferred form of my invention, what I claim as new, and desire to secure by Letters Patent, is—

1. A copying device comprising a body, the lower or working surface of which is curved, a handle attached to the body, drums mounted

to turn on the body respectively at the ends of the curved working surface thereof, a pawl and ratchet in connection with one drum adjustably to hold the same, a resilient arm attached to the other drum, and a retaining device secured to the body and adapted to hold said resilient arm.

2. A copying device comprising a body with a curved working or lower surface, a handle on the body, two drums secured to the body respectively at the ends of said curved working surface thereof, means for holding one drum against rotation, a resilient arm attached to the other drum, and a device for retaining said resilient arm in position.

In testimony whereof I have signed my name to this specification in the presence of two subscribing witnesses.

HENRY H. HARRISON.
